UNITED STATES PATENT OFFICE.

WILLIAM W. FORD, OF PHILADELPHIA, PENNSYLVANIA.

METAL COVER FOR TANKS.

Application filed May 9, 1923. Serial No. 637,911.

To all whom it may concern:

Be it known that I, WILLIAM W. FORD, a citizen of the United States, residing at 200 East Tabor Street, Philadelphia, in the county of Philadelphia and State of Pennsylvania, have invented new and useful Improvements in a Metal Cover for Tanks, of which the following is a specification.

My invention relates to new and useful improvements in a metal cover for tanks, and has for its primary object to perceptibly improve the construction of the structure set forth in my application for Letters Patent bearing Serial Number 553,843, dated April 17th, 1922.

Another object of my present invention is to provide supporting means for the ends of the T-iron rafters which are adaptable to different inclinations of said rafters.

20 A further object of this invention is to provide, in combination, a bracket and a swinging stirrup journaled or pivotally mounted in said bracket for adjustment to adapt it to the inclination of an associated rafter.

A still further object of the invention is to provide a crown supporting plate having a plurality of sockets for the reception of the upper ends of rafters.

30 With these ends in view, this invention consists in the details of construction and combination of elements hereinafter set forth and then specifically designated by the claims.

35 In order that those skilled in the art to which this invention appertains, may understand how to make and use the same, I will describe its construction in detail, referring by numerals to the accompanying 40 drawings forming a part of this application, in which:—

Fig. 1, is a vertical sectional view of a cover constructed in accordance with my invention and showing it in connection with 45 a tank, a portion of which is broken away.

Fig. 2, is an enlarged plan view of the crown supporting plate.

Fig. 3, is a sectional view thereof.

Fig. 4, is a sectional side elevation of one 50 of the stirrups and its bracket mounted on a section of a tank.

Fig. 5, is an end view of the same removed from the tank.

In carrying out my invention as herein 55 embodied, 2 represents a tank of any suitable or well known construction and made

of wood, metal or other suitable material. The upper, open end of the tank is closed by a top 3 disposed across the upper edge and preferably flush with the outer surface 60 of the side walls and said top is generally supported by a beam 4 suitably connected with the said side walls of the tank.

Fastened to the top 3, centrally thereof, is a pipe flange 5, or its equivalent, to which 65 is attached the tubular king post 6 rising any desirable height above the top 3 to provide a proper pitch for the cover. The upper end of the king post is exteriorly threaded as at 7 whereby an adjusting nut 70 8, a holding nut 9 and other elements may be mounted thereon by threaded engagement therewith.

Between the adjusting nut 8 and holding nut 9 is mounted the crown supporting 75 plate 10 having a central hole 11 for registration with the king post. Around the outer edge or circumference of the plate 10 are formed a plurality of spaced radial ears 12 in which are formed sockets 13 for 80 the reception of the inner or upper ends of the rafters 14 which are preferably formed from T-irons. The sockets are open only at the tops and outer ends, thus providing walls to assist in the support of the 85 inner or upper end of said rafters which are further supported by suitable securing means, such as bolts, inserted in the holes 15 in the side walls of the ears and passing through the rafters.

The lower end of each rafter is adapted to be inserted in the recess 16 of a stirrup 17 which has a bottom wall 18 to support the rafter and an end wall 19 to assist in taking up any endwise thrust of the rafter, the latter being held in the stirrup by suitable securing means, such as bolts, inserted in holes 20 in the side walls and passing through the rafters. The stirrup has an integral fin 21 depending therefrom which is 100 preferably of triangular shape and the inner edge of said fin forms an obtuse angle with the bottom wall of the stirrup and said inner edge of the fin has a notch 22 for registration with the upper hoop 23 of the tank. The lower end of the fin carries a pair of oppositely projecting trunnions 24.

These trunnions 24 are mounted or journaled in the spaced hooks 25 extending 110 above the upper edge of the bracket 26 having holes 27 therethrough for the passage

of fastening devices 28 to secure the bracket to the tank. This arrangement permits the stirrups to be moved toward or away from the tank to change the inclination thereof 5 so as to accommodate the different inclined positions of the rafters.

Between the rafters are located the segmental cover plates 29 which are supported by said rafters, being secured thereto in a 10 manner specified in the application above referred to or in any other suitable way.

On the upper end of the king post is mounted a frusto-conical hood 30 which forms the apex of the cover and bridges the 15 space between the upper ends of the rafters and segmental plates so as to close this open space and protect the joints between the different parts. This hood is held in place by a nut 31 having threaded engagement with 20 the king post. The king post is surmounted by a frusto-conical cap 32 having a sleeve 33 snugly fitting the bore of the king post.

From the foregoing it will be obvious that I have provided exceedingly simple and effective rafter supports which may be readily adapted to the different inclinations of the rafters thus overcoming the necessity of providing special supports for covers of different pitch.

30 Of course I do not wish to be limited to the exact details of construction as herein shown as these may be varied within the limits of the appended claims without departing from the spirit of my invention.

35 Having thus fully described my invention, what I claim as new and useful is:—

1. A support for the lower end of a tank cover rafter, comprising a stirrup closed on 40 two sides, one end and the bottom, a fin projecting from the bottom thereof and trunnions at the lower end of the fin.

2. A support for the lower end of a tank cover rafter, comprising a stirrup closed on 45 two sides, one end and the bottom, an integral fin depending from the bottom of the stirrup, the inner edge of said fin forming an obtuse angle with the bottom of the stirrup and having a notch therein and oppositely projecting trunnions at the lower end 50 of said fin.

3. A support for the lower end of a tank

cover rafter, comprising a stirrup closed on two sides, one end and the bottom, an integral fin depending from the bottom of the stirrup, the inner end of said fin forming an obtuse angle with the bottom of the stirrup and having a notch therein and oppositely projecting trunnions at the lower end of said fin, in combination with a bracket for secured to an object and a pair of spaced 55 integral hooks projecting from the upper edge of the bracket for coaction with the trunnions.

4. In combination with a tank, a king post mounted on the tank top, a rafter supporting member on said king post, adjustable rafter supporting members on the tank to correspond to the inclination of the rafters, rafters having their ends set in the several supporting members, and cover plates secured to the rafters.

5. The herein described combination with a tank, a king post supported by the top of said tank, a plurality of brackets secured to the exterior surfaces of the side walls and 75 spaced adjacent the top of the tank, spaced hooks formed with said brackets, a stirrup for each bracket, a fin formed with each stirrup, oppositely projecting trunnions carried by the lower end of the fin, the trunnions being mounted or journalled in the hooks of the brackets, a crown plate mounted on the king post, means for adjusting the height of the crown plate, a plurality of spaced ears formed about the circumference 80 of the crown plate and adapted to align with the different stirrups, said ears having sockets, rafters mounted in the sockets of the ears and socketed in the stirrups and cover plates mounted between and secured to adjacent 85 rafters.

6. A support for the upper ends of tank cover rafters, comprising a crown plate, a plurality of spaced radial ears projecting outwardly from the circumference of the 95 crown plate, said ears having sockets open at the top and outer end and further provided with holes through the side walls for the reception of securing devices.

In testimony whereof, I have hereunto 100 affixed my signature.

WILLIAM W. FORD.
